(57) **CLAIM**

The ornamental design for a panel with flow surface texture, as shown and described.

DESCRIPTION

FIG. 1 is a front perspective view of a panel with flow surface texture, showing usage in a partition structure;

FIG. 2 is an enlarged front perspective view of the central area shown in FIG. 1;

FIG. 3 is a top plan sectional view taken along line 3-3 of FIG. 5;

FIG. 4 is a left side elevation view taken along line 4-4 of FIG. 5;

FIG. 5 is a front elevation view thereof;

FIG. 6 is a right side sectional view taken along line 6-6 of FIG. 5;

FIG. 7 is a bottom plan sectional view taken along line 7-7 of FIG. 5; and,

FIG. 8 is a rear elevation view.

The broken lines showing environment in the drawings are included for illustrative purposes only and form no part of the claimed design. The outer broken line boundaries in the figures depicting the boundaries of the claimed design indicate that a specific length, width, and thickness form no part of the claimed design and are for illustrative purposes only.
